(57) **CLAIM**

We claim, the ornamental design for a sole for footwear, as shown and described.

DESCRIPTION

FIG. 1 is a bottom perspective view of a sole for footwear, showing our new design;

FIG. 2 is a bottom plan view thereof;

FIG. 3 is a top plan view thereof;

FIG. 4 is a right side view thereof;

FIG. 5 is a left side view thereof, rotated 180 degrees;

FIG. 6 is a front view thereof; and,

FIG. 7 is a rear view thereof.

The broken lines showing an elongate octagonal shape in the arch region represents an internal boundary with the lines themselves and the area within, forming no part of the claim.
